UNITED STATES PATENT OFFICE.

HELEN STEVENS BRADY, OF TACOMA, WASHINGTON.

DOOR-OPENING MECHANISM.

Application filed December 8, 1926. Serial No. 153,289.

This invention relates to devices for operating doors and has special reference to mechanism whereby a door may be opened. My invention relates more particularly to 5 doors of refrigerators, ovens, or other movable structures.

The objects of my invention are, first, to provide a means for opening the door by the foot, thereby permitting both hands 10 to be used in bearing the food or other material to be placed in the receptacle; second, to provide means for holding the door open without maintaining the foot pressure on the opening mechanism; and third, to provide means which will constantly tend to 15 keep the door closed tight, but which can be counteracted by the door-opening mechanism.

A further object is to provide a mechanism which is wholly hid from view, except the operating pedal, and is wholly mounted within the refrigerator and is 20 movable therewith and operable in all positions to which the refrigerator may be 25 moved.

Further objects are to provide such a mechanism which may be installed in refrigerators, or other places, with but very little expense, and with the least possible 30 alteration thereto, which is cheap to make, and which is very effective in use.

I attain these and other objects by the devices, mechanisms, and arrangements illustrated in the accompanying drawings, in 35 which—

Fig. 1 is an elevation of the operating hinge near the lower corner of the door; Fig. 2 is a section thereof, showing the upper portion of the operating apparatus; 40 Fig. 3 is a section of one lower corner of the refrigerator base, showing the operating pedal in elevation; Fig. 4 is a similar view of the other lower corner of the refrigerator base, showing the operating gears in elevation; Fig. 5 is a section taken at right angles to Fig. 4; Fig. 6 is a section taken at right angles to Fig. 3; Fig. 7 is a front elevation of a portion of the refrigerator base showing the hole through which the pedal 45 passes; and Fig. 8 is a front elevation of a refrigerator equipped with my mechanism, showing however the pedal passing under the refrigerator instead of through the front thereof as in Figs. 3, 6 and 7.

50 Similar numerals of reference refer to

similar parts throughout the several views. It is a very common experience that the housewife will approach the refrigerator with dishes in both hands and is obliged to lay one of the dishes down in order to 55 free her hand to open the door. This necessitates providing a table or shelf near the refrigerator, which is often inconvenient, and also results in unnecessary waste of time and effort in laying the dish down, unlatching the door, opening the door, and picking up the dish again. A similar condition also is often met with in the operation of ovens and other articles. It is to overcome these 60 objections that I have invented the herein- 65 after described means for operating the door, and though this mechanism is illustrated and described as being applied to a refrigerator it is to be understood that it may be applied with equal ease and benefit in many 70 other places. It is to be understood that this mechanism is mounted in and forms a part of the refrigerator, or other movable structure, to which it is applied and that it has no connection with the building, in 75 which it is used, and that therefore it is unnecessary to cut the floor of the building in, order to hide the operating parts from view.

It will be seen that, in the refrigerator illustrated, the cold chamber is mounted above the chamber containing the refrigerating mechanism. The cold chamber is provided with a door 1, and the lower chamber with a front-closure plate 2, having ventilating louvres 3 therein.

The door 1 is hung on a plurality of hinges, the upper hinges 4 being of usual form and construction, and the lower hinge 5 being of special construction, as herein described. A knob 6 may be provided on 90 the door 1, whereby the door may be opened if it is not desired to use the pedal mechanism.

The hinge 5 comprises a strap portion 7, secured to the door 1, and a plate portion 8, secured to the refrigerator wall. The pintle 9 for the hinge 5 passes through an upper barrel 10, on the plate 8; a central barrel 11, on the strap 7; and a lower barrel 12, on the plate 8. This lower barrel 12 is extended downward and terminates at its lower end in a hollow cylindrical casing 13. This extended portion 14 of the lower barrel 12 is of greater internal diameter 105 than the pintle 9. The cylindrical casing 13 110
